COMBUSTION CONTROL

John J. Klinker, Decatur, Ill., assignor to A. W. Cash Company, Decatur, Ill., a corporation of Delaware

Application March 18, 1937, Serial No. 131,678

4 Claims. (Cl. 158—119)

This invention relates to combustion control, and more particularly to the control of the combustion of fluent fuels, such as gas or oil.

It is ordinarily desirable in the burning of such fuels to maintain a predetermined ratio between the rate at which fuel is supplied and the rate at which air is supplied to support the combustion of the fuel. Furthermore it is also desirable to provide means whereby this ratio can be adjusted to compensate for changes in operating conditions. For example, if a change takes place in the heating value of the fuel, it will usually be necessary to make an adjustment in the fuel-air ratio in order to maintain proper combustion. This problem has been recognized, and various solutions have been proposed, but it has been considered necessary heretofore to employ complicated mechanisms, such as adjustable lever fulcrums, which are not only expensive but also likely to reduce the sensitivity of the control system.

It is accordingly one object of the invention to provide a simple and reliable apparatus for supplying fuel and air to a furnace in a predetermined ratio and for varying the ratio as may be desirable.

It is a further object of the invention to provide a simple and reliable apparatus for controlling the rate of supply of fuel and air to a furnace in accordance with the demand for heat, for maintaining a predetermined ratio between the quantities of fuel and air supplied, and for varying the ratio as may be desirable.

With these and other objects in view, as will be apparent to those skilled in the art, the invention resides in the combination of parts set forth in the specification and covered by the claims appended hereto.

In accordance with my invention in its preferred form, I utilize a fluent fuel and air as the elements of combustion, and I supply at least one of these elements to a furnace burner at a pressure above atmospheric and allow a small stream thereof to escape from a zone immediately anterior to the burner. A control force is provided which is a function of the rate of flow of the escaping stream, and this is balanced against a second control force which is a function of the rate of supply of the other element of combustion. The rate of supply of one element of combustion is regulated in such a way as to maintain a balance between these forces. Preferably the supply of fuel is controlled in accordance with the demand for heat, and the supply of air is controlled to maintain the two control forces

balanced. By varying the rate of flow in the escaping stream, I am able to control the ratio between the fuel and air supplies in a very simple and effective manner.

Referring to the drawings illustrating one embodiment of the invention, and in which like reference numerals indicate like parts,

Fig. 1 is an elevation of a steam boiler furnace and a combustion control system therefor, with certain parts shown in section;

Fig. 2 is an enlarged view of certain parts of the apparatus, partially broken away for clearness of illustration;

Fig. 3 is a view similar to Fig. 1, showing a modified form of the invention; and

Fig. 4 is a view similar to Fig. 3, showing a further modification.

The embodiment illustrated in Fig. 1 comprises a furnace 10 arranged to form a combustion chamber 11, and a steam boiler 12 associated therewith. The boiler is provided with banks of water tubes 14 and a baffle 15 of usual construction, this baffle serving to direct the hot gases from the combustion chamber into proper contact with the water tubes and thence to a gas outlet duct 16, which may lead to a suitable stack or induced draft fan (not shown). The outlet duct 16 is provided with a damper 18 having an operating arm 19. The boiler 12 is provided with the usual steam delivery pipe 20.

On the front of the furnace 10 there is mounted a burner 22 having a central fuel nozzle 23 arranged to direct a stream of fuel rearwardly into the combustion chamber 11 through an opening 24 in the furnace wall. A suitable fluent fuel, such as a combustible gas, is supplied to the nozzle 23 at a pressure above atmospheric through a pipe 26 provided with a valve 27 having an operating lever 28. The burner 22 is of the "natural draft" type, the air for combustion being forced therethrough by the pressure of the atmosphere, a sub-atmospheric pressure being maintained in the combustion chamber 11. The combustion chamber pressure, and hence the rate of air flow through the burner, is controlled by means of the damper 18.

The fuel control valve 27 is regulated in accordance with the demand for heat, and for this purpose I preferably utilize an automatic regulator 30 of the type disclosed in the United States patent to Temple No. 2,049,549. This regulator comprises a diaphragm chamber 31 and a motor 32. The diaphragm chamber 31 is connected by a pipe 34 to the steam delivery pipe 20, and the motor 32 is connected by a rod 35 to the valve 27.

lever 28. The regulator thus serves to control the valve 27 in accordance with variations in the pressure of the steam in the pipe 20.

In order to control the damper 18 there is provided a regulator 36 of the type disclosed in the United States patent to Temple No. 2,064,864. This regulator comprises a pilot valve 38 supplied with fluid under pressure from a suitable source through a pipe 39, the valve being connected by tubes 40 to a hydraulic motor 42 which is connected by a rod 43 to the arm 19 of the damper 18. The pilot valve is actuated by a lever 44 which in turn is controlled by a pair of flexible diaphragms 45 and 46 which are joined centrally by a connecting member 47. The weight of the diaphragms and associated parts is balanced by a coiled tension spring 49 which is adjustably supported by a nut 50 mounted on a screw 51.

The diaphragm 45 is subjected to an effective fluid pressure which is a function of the rate of supply of air to the furnace. For this purpose I connect the space above the diaphragm with the combustion chamber 11 by means of a pipe 52, and I connect the space below the diaphragm with the gas outlet duct 16 by means of a pipe 53. It will be apparent that with this construction the diaphragm is subjected to the pressure drop between the combustion chamber and the outlet duct, and that this pressure drop will increase as the air supply to the furnace is increased.

The diaphragm 46 is subjected to an effective pressure which is a function of the rate of fuel supply to the furnace. For this purpose there is provided a small pipe 55 through which a small stream of fuel is allowed to escape from the fuel pipe 26 at a point between the valve 27 and the burner 22 and thus from the zone immediately anterior to the burner. The escaping fuel is discharged into the combustion chamber 11 just below the burner. This pipe 55 is provided with two restrictions, one of which is adjustable. For the first restriction there is shown an orifice plate 56, and for the second restriction there is shown an adjustable valve 57. The fuel pressure between the two restrictions is transmitted to the diaphragm 46 by means of a pipe 58.

The operation of this embodiment of the invention will now be apparent from the above disclosure. Fuel flows to the burner nozzle 23 through the pipe 26, and the rate of flow is controlled by the valve 27, which is actuated by the regulator 30 in accordance with the demand for steam from the boiler 12. A small stream of fuel flows through the pipe 55, the rate of flow and the pressure between the restrictions 56 and 57 varying with the rate of flow of fuel to the burner as indicated by the pressure of the fuel anterior to the burner. The pressure between the restrictions is transmitted through the pipe 58 to the diaphragm 46, providing an upward force thereon which is normally opposed and balanced by the downward force on the diaphragm 45 caused by the pressure difference between the combustion chamber 11 and gas outlet duct 16; this pressure difference being transmitted through the pipes 52 and 53. The regulator 36 controls the damper 18 in such a way as to maintain a substantially balanced relationship between these forces. If the steam pressure drops, the regulator 30 will open the valve 27, increasing the fuel flow through the burner and through the pipe 55. This will increase the pressure on the diaphragm 46, throwing the

regulator 36 slightly out of balance and causing the motor 42 to open the damper 18. This will cause more air to enter the furnace to match the increased fuel supply, and this will increase the pressure drop between the combustion chamber and the gas outlet, thus increasing the force on the diaphragm 45 and restoring the regulator 36 to a balanced condition, whereupon the damper 18 will come to rest. If the heating value of the fuel changes, or if for any other reason it is desirable to change the ratio between the fuel and air supplies, it is merely necessary to adjust the valve 57. This will change the rate of flow in the pipe 55 and thus change the pressure transmitted through the pipe 58, causing this pressure to bear a different ratio with respect to the fuel pressure at the burner.

In Fig. 3 there is illustrated a slightly modified form of the invention in which a forced draft burner 22' is utilized, this burner being supplied with air at a pressure above atmospheric by means of a fan 60 connected to the burner by means of a duct 61. This duct is provided with a damper 62 having an operating arm 63 which is connected by a rod 64 to the motor 42 of the regulator 36. An orifice plate 66 is mounted within the duct 61 to provide a slight pressure differential for regulating purposes. A pipe 67 leads from the duct 61 anterior to the orifice plate to the space above the diaphragm 45, and a pipe 68 leads from the duct posterior to the orifice plate to the space below the diaphragm 45. The gas outlet damper 18 is preferably controlled to maintain a substantially constant pressure, slightly below atmospheric, in the combustion chamber 11, and for this purpose I may use a regulator 70 of the type disclosed in the patent to Temple No. 1,992,048. This regulator is connected to the combustion chamber by a pipe 71. Pressure fluid is supplied to the regulator 70 by a pipe 73, and tubes 74 lead from the regulator to a hydraulic motor 75 which is connected by a rod 76 to the operating arm 19 of the damper 18.

The operation of this embodiment of the invention will now be apparent from the above disclosure. The regulator 30 controls the fuel valve 27 in accordance with the steam pressure, and a small stream of fuel flows through the pipe 55 at a rate varying with the rate of fuel supply as indicated by the fuel pressure immediately anterior to the burner nozzle. The pressure between the restrictions 56 and 57 is transmitted through the pipe 58 to the diaphragm 46 and provides an upward force which is normally balanced by the downward force on the diaphragm 45 caused by the pressure difference on opposite sides of the orifice plate 66. The regulator 36 controls the damper 62 in such a way as to maintain a substantially balanced relationship between these forces, thus maintaining a predetermined ratio between the flow of fuel and the flow of air. This ratio can be easily varied by adjustment of the valve 57. Under all conditions the regulator 70 controls the damper 18 to maintain a substantially constant pressure in the combustion chamber 11.

In Fig. 4 there is illustrated a modification of the forced draft system in which the fuel pressure immediately anterior to the burner nozzle 23 is transmitted to the diaphragm 46 by means of a pipe 80. The orifice plate is omitted from the air duct 61, and a pipe 81 is connected to this duct at a point posterior to the damper 62 and thus at a zone immediately anterior to the burner. This pipe 81 is provided with two re-

strictions, shown as an orifice plate 82 and a valve 83, the arrangement being such that a small stream of air will flow through the pipe and be discharged to atmosphere. The air pressure between the restrictions is transmitted to the diaphragm 45 by means of a pipe 84.

The operation of this embodiment will now be apparent. The regulator 30 controls the fuel valve 27 in accordance with the steam pressure, and the pressure of the fuel anterior to the burner nozzle provides an upward force on the diaphragm 46 which is normally opposed and balanced by the downward force of the diaphragm 45 resulting from the air pressure transmitted thereto through the pipe 84. This air pressure is a measure of the rate of air supply to the burner 22', for if more air is supplied the pressure anterior to the burner will increase, increasing the rate of flow in the pipe 81 and causing a corresponding increase in the pressure in the pipe 84. The pressure in the pipe 80 is a measure of the rate of fuel supply, and the regulator 36 controls the damper 62 in such a way as to maintain a substantial balance between this pressure and the pressure in the pipe 84, thus varying the air supply as may be necessary to maintain a predetermined fuel-air ratio. By adjusting the valve 83 this ratio can be varied as desired. The regulator 70 controls the damper 18 to maintain a predetermined pressure in the combustion chamber 11 under all operating conditions.

It will be clear from the above disclosure that the invention provides a comparatively simple and reliable apparatus whereby the rate of combustion may be controlled in accordance with the demand for heat, and the proper ratio maintained between the supplies of fuel and air, this ratio being readily adjustable whenever desirable. This ratio adjustment is obtained without employing adjustable lever fulcrums or other similar mechanisms.

Having thus described my invention, what I claim as new and desire to secure by Letters Patent is:

45 1. Control apparatus for a combustion system having a furnace burner and utilizing a fluent fuel and air as the elements of combustion comprising a device to control the flow of air, a motor to actuate the device, a pilot mechanism to control the motor, a fluid pressure responsive device connected to the pilot mechanism to actuate the same, means subjecting the fluid pressure responsive device to a fluid pressure which is a function of the rate of supply of one element of combustion, means supplying the other element of combustion to the burner at a pressure above atmospheric, a conduit through which a small stream of said other element may escape from a zone immediately anterior to the burner under the influence of the pressure in said zone, said conduit having two restrictions therein, means subjecting the fluid pressure responsive device to the fluid pressure between said restrictions to maintain the fluid pressure responsive device in a substantially balanced condition, and means to adjust one of said restrictions and thereby adjust the ratio between the fuel and air supplies.

2. Control apparatus for a combustion system having a furnace burner and utilizing a fluent

fuel and air as the elements of combustion comprising a damper to control the flow of air, a motor to actuate the damper, a pilot mechanism to control the motor, a fluid pressure responsive device connected to the pilot mechanism to actuate the same, means subjecting the fluid pressure responsive device to a fluid pressure which is a function of the rate of supply of the air, means supplying the fuel to the burner at a pressure above atmospheric, a conduit through which a small stream of the fuel may escape from a zone immediately anterior to the burner and thence past the burner to the combustion space under the influence of the pressure in said zone, said conduit having two restrictions therein, means subjecting the fluid pressure responsive device to the fluid pressure between said restrictions to maintain the fluid pressure responsive device in a substantially balanced condition, and means to adjust one of said restrictions and thereby adjust the ratio between the fuel and air supplies.

3. Control apparatus for a combustion system having a furnace burner and utilizing a fluent fuel and air as the elements of combustion comprising means to supply both the fuel and the air to the burner at a pressure above atmospheric, a damper anterior to the burner to control the flow of air, a motor to actuate the damper, a pilot mechanism to control the motor, a fluid pressure responsive device connected to the pilot mechanism to actuate the same, means subjecting the fluid pressure responsive device to a fluid pressure which is a function of the rate of supply of the air, a conduit through which a small stream of the fuel may escape from a zone immediately anterior to the burner and thence past the burner to the combustion space under the influence of the pressure in said zone, said conduit having two restrictions therein, means subjecting the fluid pressure responsive device to the fluid pressure between said restrictions to maintain the fluid pressure responsive device in a substantially balanced condition, and means to adjust one of said restrictions and thereby adjust the ratio between the fuel and air supplies.

4. Control apparatus for a combustion system having a furnace burner and utilizing a fluent fuel and air as the elements of combustion comprising means to supply both the fuel and the air to the burner at a pressure above atmospheric, a damper anterior to the burner to control the flow of air, a motor to actuate the damper, a pilot mechanism to control the motor, a fluid pressure responsive device connected to the pilot mechanism to actuate the same, means subjecting the fluid pressure responsive device to the pressure of the fuel immediately anterior to the burner, a conduit through which a small stream of the air may escape from the zone between the damper and the burner under the influence of the air pressure in said zone, said conduit having two restrictions therein, means subjecting the fluid pressure responsive device to the fluid pressure between said restrictions to maintain the fluid pressure responsive device in a substantially balanced condition, and means to adjust one of said restrictions and thereby adjust the ratio between the fuel and air supplies.

JOHN J. KLINKER.
